UNITED STATES PATENT OFFICE

1,993,935

ACCELERATOR

Henry W. Lane, Ione, Calif.

Application February 8, 1933, Serial No. 655,804

2 Claims. (Cl. 74—513)

The invention relates to motor vehicles and more particularly to the means by which the throttle valve of the engine is operated.

One object of this invention is to provide a novel and simple device by means of which the throttle valve of an engine may be operated by a lateral movement of the foot and of such novel construction that it may be attached to the usual foot accelerator now in common use on automobiles.

Another object is to provide a device of this character which may be readily attached to the common type of automobile as it is all placed above the toe and floor board and for that reason can be quickly installed.

A further object is to provide a device of this character embodying a shoe engaging roller adapted to reduce to a minimum friction in operation and so constructed that the sole of the shoe only will come in contact with the roller and thus prevent the upper part of the shoe from soil or wear in operating the accelerator.

With the above and other objects and advantages in view, the invention consists in the construction, and the arrangement and combination of parts more fully described and claimed, and illustrated in the accompanying drawings in which:

Figure 1 is a side elevation, partly in section, showing the invention installed on the toe board of an automobile.

Figure 2 is a top plan view of the device.

Figure 3 is a side elevation of the frame and movable parts removed from the housing.

Figure 4 is a side elevation showing the depression plate and the depression arm at the end of their downward movement.

Figure 5 is a side elevation of the depression arm in its raised position.

Figure 6 is a top view of one form of foot accelerator pedal showing my depression plate secured thereto.

In the drawings which show a preferred embodiment of my invention, the numeral 1 designates the cowl of an automobile, 2 designates the hood, 3 the dash, 4 the toe board, and 5 the floor board which taken together serve to locate the position of my invention.

The usual operating rod 39 is connected to the throttle valve of a carburetor (not shown) and the other end extends upward through a hole in the toe board where it is engaged by my invention, which embodies a housing 7 secured to the toe board by means of screws and lugs 40,

41 and 42 and is located to the right of the brake pedal 9 and clutch pedal 8.

The only operating part above the housing is the roller 12 mounted to turn on a stud 13 which moves in a slot 17 provided in the housing. Sleeve 18 is threaded and screws onto stud 13 thus forming a shoulder at 14 which prevents the roller from sliding down on the stud and rubbing on the housing. The roller is provided with a bushing 10 and is held on the stud 13 by its head. A flange 11 is provided on the base of the roller and is adapted to be engaged by the sole of the operator's shoe and will thereby prevent the upper part of the shoe from touching the roller or from becoming soiled thereby. The lower part of the stud is threaded and is screwed into a threaded hole in the end of the lever 16 and a nut 15 serves as a lock nut to prevent it from loosening.

The lever 16 is secured to a sector 19 by means of a screw 20 and a slotted end at 21 which fits partly over a bolt 22. The sector 19 which is shown in Figs. 2 and 3 is provided with teeth shown at 29 which mesh with the teeth of a pinion 28. This pinion is rigidly secured to the end 25 of a shaft 30. A guide 43 is provided to hold the sector in mesh with the pinion.

A bracket 24 is secured within the housing by means of screws 26 and 27 and serves as a frame to hold the sector 19 and the pinion 28. It is 30 provided with a journal 25 in which the shaft 30 finds its bearing. The sector turns on the bolt 22 which passes down through the bracket and is held by a nut 23. The other end of the shaft 30 finds its bearing in the forward end of the 35 housing 7.

A depression arm 31 is secured to the shaft 30 by means of a clamp screw 32 and is adapted to engage a plate 34 attached to the end of the rod 39 which leads to the throttle valve of the carburetor. The depression arm is provided with a hook 33 formed on its end to engage the plates 34 or 35.

Some cars are provided with a throttle valve lever 38 in place of a button on the end of a 45 throttle valve rod 39 and to adapt my device to this type of foot accelerator I have provided a plate 35 to be attached to the lever by means of a bolt 37 and clips 36 adapted to be bent over the lever.

The operation of the device is as follows:

When it is desired to accelerate the speed of the motor the operator causes the sole of his shoe to engage the flange of the roller 12 causing it to move across the top of the housing above 55

the slot 17 and since the roller is secured to the end of the lever 16 and lever 16 is secured to the sector 19 the upper end of lever 16 is moved to the right thereby turning the sector on bolt 5 22. The teeth of the sector being in mesh with the teeth of the pinion 28 rigidly secured to shaft 30 the shaft is caused to turn and in doing so the depression arm 31 engages the depression plate 34 or 35 as the case may be, depending on the type 10 of car operated, and since the plate is secured to the usual accelerator rod 39 it is pushed forward and downward in the accustomed manner to accelerate the speed of the motor. When the 15 roller of the operator is moved away from the roller the usual spring (not shown) returns the accelerator rod to its normal position which in turn moves the operating parts of my device to their normal position.

It is to be understood that the form of my invention, herewith shown and described is a preferred 20 example of the same, and that various changes may be made in the shape, size and arrangement of parts without departing from the spirit of my invention or the scope of the accompanying claims.

25 It will now be seen that I have provided an accelerator for automobiles and the like which will not be tiresome to the operator because his foot rests firmly upon an immovable housing and that the speed of the motor will remain constant 30 while traveling over rough and bumpy roads because the movement of the foot in operating the device is lateral instead of up and down.

What I claim is:—

1. A foot accelerator including a housing, a slot provided therein, a foot lever fulcrumly mounted in said housing, a stud secured to one end of said foot lever and adapted to travel in said slot, a roller mounted on the upper end of said stud and adapted to turn thereon, a sector provided with teeth and to which said foot lever is secured, a shaft and a pinion rigidly secured thereto and adapted to mesh with the teeth of the sector, 10 an arm rigidly mounted on said shaft a plate mounted on the conventional foot accelerator pedal or parts leading to the throttle valve of the carburetor and adapted to be engaged and moved forward by said arm. 15

2. A foot accelerator including a housing, a slot provided therein, a foot lever fulcrumly mounted in said housing, a stud secured to one end of said foot lever and adapted to travel in said slot, a roller provided with a flange extending around 20 its base and mounted on the upper end of said stud and adapted to turn thereon, a sector provided with teeth and to which said foot lever is secured, a shaft and a pinion rigidly secured thereto and adapted to mesh with the teeth of the sector, an arm rigidly mounted on said shaft, 25 a plate mounted on the conventional foot accelerator pedal or parts leading to the throttle valve of the carburetor and adapted to be engaged and moved forward by said arm. 30

HENRY W. LANE.
